ENGINE STARTING MECHANISM

Romeo M. Nardone, Westwood, N. J., assignor to
 Bendix Aviation Corporation, South Bend, Ind.,
 a corporation of Delaware

Application October 6, 1941, Serial No. 413,872

3 Claims. (Cl. 123—179)

This invention relates to engine starting mechanism and more particularly to a starting mechanism of the inertia type, in which there is a period of energy storage in an "inertia" element (flywheel, for example) prior to movement of the engine engaging, or cranking element, to cranking engagement with the member of the engine to which initial rotary movement is to be imparted.

In inertia starters as heretofore known an appreciable amount of energy accumulated in the flywheel is lost—first, through the slippage of an overload release clutch and secondly, by the fact that some energy remains unused at the moment when the engine "starts"; and even on the occasions when the cranking effort is continued until the flywheel energy is used, the energy remaining at speeds below 4000 R. P. M. is ineffective, due to the low engine cranking speed from that point down to zero. In other words, on such occasions, there is a failure of the engine to "start." Further, inertia starters engage at maximum rotary speed, thereby imposing a torque value on the engine member which is normally above the slipping value of the overload release clutch. This tends to create a condition of shock, at first engagement.

Objects of the present invention are to make advantageous use of all the energy of the flywheel all the way down to zero flywheel speed; and to minimize the shock of engagement. The latter I propose to bring about by engaging the starter and engine jaws at zero rotary speed, thereafter increasing the rotative speed of the starter jaw.

Another object is to crank the engine at speeds over and above that which would normally obtain with a fixed gear ratio between flywheel and engine engaging jaw, the cranking speed being characterized by a tendency to increase during at least the initial stage of the run-down period of the flywheel, rather than to decelerate therewith, as has been the tendency heretofore.

Still another object is to produce a direct cranking action by use of energy from a prime mover additional to the flywheel, said prime mover being operative, first, to accelerate the flywheel, and subsequently—upon reversal in its direction of rotation—being instrumental in establishing connection between the starter and engine, and also in helping the flywheel to speed up the engine and continue to transfer energy thereto even after the flywheel has come to a complete stop, and so long as is necessary to insure effective starting.

These and other objects of the invention will become apparent from inspection of the following specification when read with reference to the accompanying drawings wherein is illustrated the preferred embodiment of the invention. It is to be expressly understood, however, that the drawings are for the purpose of illustration only, and are not designed as a definition of the limits of the invention, reference being had to the appended claims for this purpose.

In the drawings:

Fig. 1 is a central sectional view of a device embodying the invention;

Fig. 2 is a very partly in section and partly in elevation of a modified embodiment of the starter shown in Fig. 1; and

Fig. 3 is a diagram of electrical parts and connections applicable to control energization of the motor of Fig. 1 or Fig. 2.

The invention is illustrated in the accompanying drawings as embodied in a housing having an outer section 3 and an inner section 4 with a suitable flange 5 to receive bolts 6 for detachably connecting said sections. The inner section 4 is provided with a second flange 7 to receive bolts 8 for securing the starter to the crankcase of an engine, a portion of the latter being indicated at 9. Secured to one side (top, as shown) of section 3 is an electric motor 10 provided with a casing 11 having a flange to register with a corresponding flange on casing section 3, and be supported thereby.

The motor may be of any suitable type embodying an armature shaft 13 provided with a projecting, reduced portion 14 that is rotatably mounted as by means of a suitable bearing 15 in a transversely extending wall of housing section 3. Drivably connected to the reduced portion of the armature shaft is a pinion 16 that meshes with a bevel gear 17 which, in the form shown, is integral with an internally toothed annular gear 18. Adjacent the member 18 is a cylindrical boss 19 forming part of the end wall of housing section 3. The boss 19 supports therein a double bearing 20 within which rotates the hub 21 of the flywheel 22, also the shaft 23 to which said hub 21 is keyed as indicated. Said shaft 23 also has keyed thereto a ratchet toothed clutch element 24, and at its opposite end the shaft is formed into a pinion, as at 26, constituting the "sun," or central element of a planetary system whose several planet pinions, as at 27 and 28, mesh with the orbital gear 18 heretofore referred to. A second ratchet element 31 is splined upon stationary sleeve 32 embedded in

rear cover plate 33, and a smaller cover plate 34 holds in position a spring 36 which yieldably urges the ratchet element 31 into mesh with ratchet element 24, thereby restricting flywheel 22 to rotation in a single direction only.

A second planetary system includes a planet carrier 38 integral with a sun gear 39, and is rotatably mounted as by means of a bearing 41 on a stub shaft 42 that extends outwardly from, and is drivably connected to, a barrel 43 having a closed end 44, the stub shaft being integral with said closed end in the illustrated embodiment of the invention. Ball bearings 30 carried by the inner housing section 4 are preferably employed for rotatably mounting the barrel 43.

Gear 39 meshes with a plurality of planetary gears 46 that are rotatably mounted on the barrel end 44 and mesh with an annulus gear 47 which is fixedly mounted within the housing by means of studs 48. Preferably three planetary gears 46 are employed, and one of these is shown in section in Fig. 1. These gears 31 are preferably spaced 120° apart, so that as the view is taken in Fig. 1, one of the gears appears in elevation just below the stub shaft 42. Each of the planetary gears 46 (and the same is true of planets 27, 28) is rotatably mounted by means of a ball bearing, as at 51 carried by a sleeve which is countersunk at its inner end in barrel end 44. A screw 52 supports each sleeve, bearing and planetary gear. If desired, a retaining ring 53 for the bearings 51 may be provided, as an integral part of the screw receiving sleeves.

As shown, annulus 47 has two orbital tracks, the second being engaged by planet pinions 56 rotatably mounted (by parts similar to those supporting pinions 51) to turn with carrier 38 above described, and each meshing with a sun gear 57 formed on one end of a shaft 58 connecting said gear with the carrier 59 of the planets 27, 28. A second ratchet clutch has one element 61 integrated with planet carrier 38, the adjacent element 62 being splined to stationary boss 63 of transverse wall 64. Springs 65 urge clutch part 62 into engagement with part 61, to restrict rotation of planet carrier 38 to a single direction.

The electric motor 10 is adapted to drive an engine engaging member 64 through the train of reduction gearing described above. The member 64 constitutes one element of a jaw clutch, the other element being formed by a member 66, carried by a rotating part of the engine to be cranked, such as the engine crankshaft or an extension thereof. There is also preferably employed the usual multiple disc clutch embodying a plurality of friction disks 69, a number of said disks being splined to the inner surface of barrel 43, and the remainder being splined to the outer surface of an interiorly threaded nut 71. Resilient means such as a plurality of coil springs 72 and an adjusting nut 73, which is threaded into the inner end of barrel 43, are provided for varying the pressure with which disks 69 are maintained in engagement.

Mounted for rotary and longitudinal movement within nut 71 is the usual threaded shaft 74 which is longitudinally splined at its inner end to drivably engage a correspondingly splined, tubular and outwardly extending portion 64a of the jaw clutch member 64. Movement of threaded shaft 74 to the left, as viewed in Fig. 1, relative to nut 71 is positively limited by means of a member 76 threaded on the outer end of shaft 74 and constituting a stop for engagement with a shoulder formed interiorly of nut 71. Prefer-

ably a coil spring 78 is interposed between jaw clutch member 64 and shaft 74, a portion of said spring extending into a recess formed in the inner end of the shaft, to yieldably resist relative movement of the parts.

The starter is preferably provided with the usual oil sealing means for preventing oil in the engine crankcase 9 from seeping into the starter housing. This includes a cup-shaped member 81 that is preferably formed of metal and is provided with a flange 82 on the outer end thereof, said flange being adapted to be clamped between flange 7 of the starter housing and the engine crankcase. The inner portion of member 81 is bent inwardly toward jaw member 64, and is provided with a central opening which is slightly larger in diameter than the outer diameter of the head of jaw member 64.

In order to prevent seepage of oil through the central opening in member 81, the latter preferably carries the usual washer of leather or the like, secured in any suitable manner to the shoulder provided adjacent the bend of member 81. Normally the inner portion of the washer is held in engagement with the adjacent surface of the head of jaw member 64 by means of a sleeve which slidably surrounds the cylindrical portion 64a of the jaw clutch member and abuts at its outer end against a flange provided on nut 71. The outer periphery of the head of member 81 is provided with longitudinally disposed slots adapted to receive radial lugs which project inwardly from the inner surface of a split-ring 91 that is supported on the curved lip of the oil seal member 81. The several portions of the split-ring 91 are preferably retained in position on member 81 by means of a surrounding resilient member, such as a coil spring 92, which rests in a circular groove formed in the outer periphery of said ring 91. The latter is adapted to rotate on the curved lip surrounding the central opening in member 81; this construction being more fully illustrated in Patent No. 1,962,397 granted to Raymond P. Lansing on June 12, 1934.

There is also preferably provided the usual rod 96 which slidably extends through stub shaft 42, barrel end 44, threaded shaft 74 and a central opening in the hub member 81. The inner portion of rod 96 is of reduced diameter to provide a shoulder 90 which normally abuts against the outer end of shaft 74. The inner end of rod 96 is threaded to receive a nut which abuts the hub of jaw member 64 and coats with shoulder 90 to retain said member and shaft in operative relationship.

During flywheel acceleration, all planetary spiders are stationary and therefore the starter barrel 43 does not rotate. After proper flywheel speed is obtained, the direction of motor rotation is reversed by any suitable circuit arrangement (as in Fig. 3 hereinafter described), as by cutting off the current in one set of field coils and sending it through a second set of field coils. When this circuit change is made, the motor rapidly decelerates to zero, under the action of the reverse current, and the speed of gear 18 in its original direction of rotation is thereby decreased. This decrease in speed of gear 18 causes all planets to rotate, which rotation is of course communicated to the starter barrel 43. This results in immediate screw action at 71, 74, whereupon starter jaw 64 starts to move forward into engagement with the engine jaw. Engagement is therefore at zero speed and zero torque; hence there is no slippage at

clutch 69. However, during this deceleration of the motor to zero speed some flywheel energy is lost, due to the drag of the decelerating gear 18 upon the flywheel; but this loss is slight as compared with what is saved by reason of the absence of any slippage at clutch 69. After reaching zero speed the motor will start to rotate in the reverse direction, speeding up gear 18, also in the reverse direction, and thereby increasing the speed of the planetary system and hence of the starter jaw 64. Flywheel 22 will eventually come to a complete stop, but during the period of its deceleration the speed of gear 18 will approach that of gear 26 and eventually overtake it and pass it. In this way rotation of spider 59 is caused to continue even after the flywheel has stopped.

As the flywheel comes to zero speed, clutch 31, 24 takes hold and prevents its rotation in the reverse direction. Gear 18 continues to be rotated by the motor and the engine is cranked at a speed corresponding to motor speed divided by the ratio between it and the jaw 64. Direct cranking (from motor 10 to jaw 64) may thus continue until the engine "starts." Maximum torque at the jaw 64 is a function of the maximum torque of the motor during its reversal, and the gear ratio between motor and jaw. This torque must in all cases be appreciably higher than the breakaway torque of the engine. Were it not so, the engine would not move, and all the energy in the flywheel would be expended in rotating the motor armature against its electrical torque.

In some installations it may be preferred to employ an added element to facilitate the action of reversing the direction of motor rotation after acceleration of the flywheel. Such an element may take the form of a brake engageable with a suitable surface on the armature shaft or other rotating part of the motor; and as illustrated in Fig. 2 such a brake may consist of a pair of cone clutch elements 101 and 102 normally held engaged by springs 103; said springs being yieldable to permit movement of the outer element 102 to the disengaged position upon passage of current through a winding 104 of an electromagnet whose plunger type armature is thereby shifted to produce such disengaging movement of the element 102, through the action of a yoke 106, pivotally mounted at 120, and mechanically linked to the magnet plunger 107 as shown in Fig. 2.

Winding 104 is shown as being in circuit with a source 105 and a switch 108 (Fig. 3) when the latter occupies a position of engagement with either contact 111 or contact 112, these being the contacts controlling shunt field coils 116 and 117, respectively, and hence controlling the direction of rotation of the motor 10, whose armature winding is indicated at 115 in Figs. 2 and 3. Thus it will be apparent that the brake will be ineffective so long as current is flowing to the motor windings, but will immediately become effective as the switch 108 is moved away from contact 111, and toward contact 112, preparatory to reversal of the direction of rotation.

If the motor is of the "series field" type, the circuit will be as shown in Fig. 4.

Even without a reversal of rotation of the motor, the brake 101, 102 is useful as a means of arresting motor rotation and thus facilitating release, to the jaws 64, 66, of the energy previously stored in the flywheel 22; for, as heretofore noted, any reduction in motor speed immediately produces a corresponding reduction in the speed of gear 18, and thereby causes the planets to rotate and the jaw 64 to move forward into engine engaging position. Thus energy transfer to the jaws 64, 66 begins as soon as the rotation of motor 10 is retarded; and as such energy transfer may frequently be sufficient to "start" the engine even before complete dissipation of the stored energy of the flywheel, there is no necessity, under such conditions, to resort to continued motor operation.

This application is a continuation-in-part of my copending application Serial No. 296,681, now Patent No. 2,279,126.

What is claimed is:

1. In an engine starter, the combination of an engine engaging member, a rotatable gear carrying member, means for transmitting the rotation of said gear carrying member to said engine engaging member, means for rendering said rotation transmitting means ineffective during force application to said gear carrying member in one direction, and means for reversing the direction of force application upon said gear carrying member, said last named means including a prime mover and a brake having one element rotatable with said prime mover, and a second non-rotatable element, a switch controlling energization of said prime mover, means responsive to closing of said switch to cause disengagement of said two braking elements, and means responsive to opening of said switch to cause engagement of said two braking elements.

2. In an engine starter, the combination of an engine engaging member, a rotatable flywheel, means for transmitting the rotation of said flywheel to said engine engaging member, means for rendering said rotation transmitting means ineffective during force application to said flywheel in one direction, and means for reversing the direction of force application upon said flywheel, said last named means including a prime mover and a brake having one element rotatable with said prime mover, and a second non-rotatable element, a switch controlling energization of said prime mover, means responsive to closing of said switch to cause disengagement of said two braking elements, and means responsive to opening of said switch to cause engagement of said two braking elements.

3. In an engine starter, the combination of an engine engaging member, a rotatable flywheel, means including an electric motor for storing energy in said flywheel, independently of any rotation of said engine engaging member, and means for subsequently transferring said stored energy to said engine engaging member, said last-named means including cooperating brake elements for arresting rotation of said energy storing means, and means responsive to engagement of said brake elements to cause release of the stored energy.

ROMEON M. NARDONE.
